UNITED STATES PATENT OFFICE.

JOEL STUBBS, OF LONG LAKE, MINNESOTA.

EVAPORATING-PAN.

SPECIFICATION forming part of Letters Patent No. 240,621, dated April 26, 1881.

Application filed March 10, 1880. (No model.)

To all whom it may concern:

Be it known that I, JOEL STUBBS, of Long Lake, in the county of Hennepin and State of Minnesota, have made certain Improvements 5 in Evaporating-Pans for Sugar and Sirup Making, of which the following is a specification.

This invention relates to evaporating-pans used in the manufacture of sugar, sirup, &c.; 10 and it consists in a shallow metallic pan having one end semicircular, and a partition running longitudinally through the center nearly to the rounded end, dividing the pan into two compartments, and an adjustable gate shutting off a portion of one compartment to form 15 a finishing-chamber, as hereinafter set forth.

The invention further consists in extending one of the longitudinal compartments beyond the other, so that the flame and smoke may be 20 carried beyond and around the finishing-chamber and not affect it, as hereinafter set forth.

The invention further consists in a partition dividing the arch of the furnace into two compartments, and providing said partition with 25 a series of dampers, so that the direction of the flame and smoke may be controlled to regulate the degree of heat beneath the different parts of the pan, as hereinafter set forth.

In order that those skilled may know how 30 to make and use my improved evaporator, I will proceed to describe its construction and operation, referring by letters to the accompanying drawings, in which—

Figure 1 is a plan view of my improved 35 evaporator; Fig. 2, a horizontal section taken at the line $y-y$, Fig. 3; Fig. 3, a vertical central section taken longitudinally; Fig. 4, a cross-section at xx , Fig. 2; Fig. 5, a detail perspective view of the steam-drum, partly in vertical section; and Fig. 6, a detail view of the steam-drum and pipes connected therewith.

A is the foundation, and B the side walls, of the furnace, made of brick in the usual manner.

45 The pan is set upon top of the side walls, as shown, and is divided longitudinally by a partition, a , into two compartments, C' C^2 , one end of the pan being semicircular in form, as shown at b , and a space left between it and 50 the end of the partition a for the passage of the juice from one compartment to the other.

The compartment C' will be extended beyond the compartment C^2 at c , and provided with an incline, d , for the reception of the juice, this extension removing that part of the 55 compartment beyond the end of the finishing-chamber, so that the fire from the furnace may be carried around the finishing-chamber and not affect it, as hereinafter set forth.

e is a gate or valve, which shuts off a portion of the rear end of the compartment C^2 to form a finishing-chamber, C^3 , as hereinafter explained.

E is a hollow metallic drum set upon or through a plate resting upon the side walls, 65 B, and partition-wall passing through the arch, from the bottom of which a pipe, F, runs back to the grate G of the furnace. This grate will be formed of gas-pipe or other tubing, of which the pipe F is an extension, so that when the 70 grate, pipe, and part of the drum are filled with water steam will be generated by the heat of the fuel used in the furnace, and fill the space g above the water in the drum E. (See Fig. 5.)

75 From a point near the top of the drum E a smaller pipe, H' , branches, and is connected by a pipe-hinge, h' , to a similar pipe, H^2 , which is run down into and back and forth along the bottom of the finishing-chamber C^3 , and thence 80 up again to a second pipe-hinge, h^2 , exactly opposite to and acting in conjunction with the first hinge h' , from which point a third pipe, H^3 , projects downward into a water-tank, I, (see Fig. 4,) by which the steam is condensed. 85 By this means steam is conducted through the nest or coil H^2 in the bottom of the finishing-chamber to furnish the required heat for finishing the sirup by steam, while the hinged joints h' h^2 enable the coil to be raised up out 90 of the chamber, as shown in Fig. 3, when not in use, or for cleaning or removing the pan, or for any other purpose.

Through the center of the fire space or arch of the furnace a brick or other wall, K, is 95 formed, which divides the arch into two longitudinal compartments, L' L^2 , corresponding with and directly beneath the compartments C' C^2 and finishing-chamber C^3 of the pan. This wall K is pierced at i for the passage of 100 the smoke and flame from the compartment L' into the compartment L^2 , and thence into the

flue M, which will be set above and communicating with the rear end of the compartment L². This wall K is also pierced at intervals throughout its length, and provided at these openings with dampers m' m² operated by rods n' n² from outside the walls B, and adapted to reach from the center wall to the side walls, as shown in Fig. 2, so that the fire and smoke may be made to take the course indicated by 10 arrows in Fig. 2 and thus throw all the heat into one of the longitudinal compartments. By varying the positions of these dampers, however, the course of the fire may be altered to almost any desired degree. Thus by placing 15 both dampers in a line parallel with the wall K nearly an equal amount of flame will pass through each compartment L' L², consequently the pan will be subjected to an equal heat at all points; or if it is desired to produce a 20 greater heat at some points than at others it may be accomplished by manipulating the dampers, as will be readily seen.

By closing the damper m² and leaving the damper m' as shown in Fig. 2 all the flame will 25 be carried through one compartment, L', and into the smoke-stack M through the flue i, leaving the finishing-chamber C³ entirely unaffected by the direct action of the heat from the furnace, which is a great advantage when it is 30 desired to finish the syrup by the heat of the steam-pipes H² alone, the compartments C' and L' extending beyond the finishing-chamber for this purpose.

By increasing the number of the dampers 35 m a still greater variety of changes may be given to the draft.

The pan being set about one inch lower at the forward end than at the rear end, the juice will flow toward that end, and will become 40 gradually heated as it approaches the semicircular end b, at which point the heat is greatest, and will flow around the partition a into the compartment C² until stopped by the gate e. When the juice has been boiled long 45 enough to evaporate that part of it on the semicircle b and in the compartment C² into a semi-syrup the gate e is opened and the syrup allowed to run into the finishing-chamber C³ until it is level with the remainder of the 50 juice in the pan. Then the gate e is closed and the steam in the drum E turned into the coil H², and the finishing or reduction to syrup proper conducted by the heat of the steam alone, the dampers m' m² being turned at the 55 proper stage, as before described, to turn all the heat of the furnace into the compartment L', so that the finishing may be done by the heat of the steam alone.

By my arrangement of the two compartments connected by the semicircle b no square corners are left, in which eddies are formed or dead juice left to be injured by the intense heat. The round end also prevents a large

amount of friction, and is a very important feature of my invention.

The upper edges of the sides of the pan and partition a will be provided with wooden strips u, which extend down some distance below the edge of the metal, and thus not only act as stiffening-pieces to the pan, but, wood being a non-conductor of heat, act as coolers to 70 keep the foam down and prevent its overflowing.

While the juice is flowing from the incline d to the compartment C² scum and foam are 75 formed upon its surface, the first or green scum being caused by the impurities in the juice; but as the heat increases these impurities rise to the surface and form the green scum, and as the juice becomes purer the foam 80 becomes whiter, so that the operator is able to judge of the purity of the juice by the appearance of the foam. When the juice reaches the point b the increased heat raises the foam six or eight inches high, causing a backward 85 movement of the foam toward the thin juice at d, carrying with it the green scum, so that none of the green scum passes into the compartment C² or finishing-chamber C³.

I am aware that it is not new, broadly, to 90 construct evaporating-pans with the border curved at the corners or throughout their extent.

I am also aware that it is not new, broadly, to divide an evaporating-pan by longitudinal 95 or transverse partitions, and do not wish to be understood as claiming any such construction broadly; but

What I claim as new, and desire to secure by Letters Patent, is—

1. The evaporating-pan formed into two compartments, C' C², by a longitudinal partition, a, extending not quite to the end, leaving a curved passage, the compartment C² being divided transversely by a gate, e, to form a finishing-compartment, C³, and the compartment C' extending beyond the compartment C³, in combination with the furnace, divided longitudinally, as described, and pierced at i, and provided with the dampers M' M², whereby the finishing-chamber may be protected from the fire and smoke, substantially as hereinbefore set forth.

2. The compartments C' C², joined at one end by a curved channel, b, and divided longitudinally by the partition a, in combination with the gate e, whereby a third compartment is made, as hereinbefore set forth.

In testimony whereof I have hereunto set my hand in the presence of two subscribing witnesses.

JOEL STUBBS.
